UNITED STATES PATENT OFFICE.

TOMASO DI TERLIZZI, OF SOMERVILLE, MASSACHUSETTS.

ENVELOP-ATTACHING CLIP.

1,171,707.

Specification of Letters Patent. Patented Feb. 15, 1916.

Application filed April 6, 1915. Serial No. 19,614.

To all whom it may concern:

Be it known that I, TOMASO DI TERLIZZI, a subject of the King of Italy, residing at Somerville, in the county of Middlesex and State of Massachusetts, have invented new and useful Improvements in Envelop-Attaching Clips, of which the following is a specification.

The invention relates to envelop attaching devices, and more particularly to the class of envelop attaching clips for parcel post packages.

The primary object of the invention is the provision of a device of this character wherein the letter contained within an envelop can be securely fastened to a parcel post package so as to be safe in transit therewith without possibility of the loss of the same when the package is being carried in the mails from one point to another.

Another object of the invention is the provision of a device of this character which is extremely simple in construction, readily and easily applied to both the cord or string of the parcel post package and the envelop, thoroughly reliable and efficient in its purpose, and inexpensive in manufacture.

With these and other objects in view, the invention consists in the construction, combination and arrangement of parts as will be hereinafter fully described, illustrated in the accompanying drawing, and pointed out in the claims hereinafter appended.

In the drawing: Figure 1 is a plan view of a parcel post package and envelop showing the device constructed in accordance with the invention attaching the envelop to the package. Fig. 2 is a perspective view of the device detached. Fig. 3 is a vertical sectional view on the line 3-3 of Fig. 1.

Similar reference characters indicate corresponding parts throughout the several views in the drawing.

Referring to the drawing in detail, A designates a parcel post package, which is wrapped and tied in the usual manner through the medium of a string or cord B, while the envelop C containing a letter is attached by the device hereinafter fully described.

The device comprises a clip formed from

a single piece 5 made from metal provided with widened terminals or ends 6 and 7, respectively, and is folded at 8 to provide 55 a bight for receiving a stretch of the string or cord B, while formed in the ends 6 and 7 are spaced transverse slots 9 through which are adapted to be trained bendable tongues 10 cut from the piece 5 for the 60 fastening of the ends of the envelop C, the slots 9 contained in the ends 6 being in alinement or in registration with similar slots 11 formed in the said piece 5 for the 65 fastening of the open end of the envelop 70 closed as shown. The ends of the tongues are concealed by engaging the same in a manner as shown in the drawing so that they will not become freed with resultant possibility of the loss of the envelop when in transit with the parcel post package.

The device is attached to the envelop by passing the tongue 10 on the folded end of the clip through the front and back of the envelop C, the said tongue being guided 75 through the slots 9 and 11 as it is trained through the body of the envelop, while the other tongue is passed through the sealing flap D and the back of the said envelop C, and this tongue is guided through the slots 80 9 provided therefor, the application of the clip being clearly shown in Fig. 3 of the drawing.

It will be apparent that the sealing flap D of the envelop C is securely fastened to 85 the body of the said envelop, and the open end of the envelop is fastened closed by the clip which is carried upon the string B trained about the parcel post package A so that the envelop will be a part thereof 90 for the carriage of the same through the mail.

What is claimed is:—

1. A device of the class described comprising a strip having enlarged terminals 95 provided with spaced slots, the said strip being bent near one terminal to form a bight for receiving a cord, and means cut from the strip at the terminals thereof and engaged with the slots for fastening the 100 strip to an envelop at two points thereof.

2. A device of the class described comprising a strip having enlarged terminals provided with spaced slots, the said strip

being bent near one terminal to form a bight for receiving a cord, and bendable tongues cut from the strip at the terminals thereof and adapted to be threaded through the slots for the fastening of the strip to an envelop at two points thereof.

In testimony whereof I affix my signature in presence of two witnesses.

TOMASO DI TERLIZZI.
